UNITED STATES PATENT OFFICE.

MAXIMILIAN WEIL, OF NEW YORK, N. Y., ASSIGNOR, BY MESNE ASSIGNMENTS, TO AUTOMATIC RAILWAY CONTROL COMPANY, INC., OF NEW YORK, N. Y., A CORPORATION OF NEW YORK.

INDUCTION TRAIN CONTROL.

1,258,626.

Specification of Letters Patent.

Patented Mar. 5, 1918.

Application filed March 8, 1913. Serial No. 752,868.

To all whom it may concern:

Be it known that I, MAXIMILIAN WEIL, a citizen of the United States, residing at New York city, in the county of New York and State of New York, have invented certain new and useful Improvements in Induction Train Controls, of which the following is a full, clear, and exact specification.

- 10 This invention relates to means for automatically controlling the speed of a locomotive or other vehicle by electroinductive devices operated without physical contact with a roadside device, said electroinductive devices being operative upon increase of current through one coil of a transformer carried in part on the vehicle and in part externally thereof, but adapted to be in inductive relation at certain predetermined points.
- 15 According to the preferred form of the invention shown in the accompanying drawing, a portion of the core together with the primary coil is mounted upon the vehicle, and in inductive relation to the remaining portion of the core, which may be constituted ordinarily by the track rail, the latter at predetermined control points being magnetically interrupted, but associated at such points with a magnetic bridge having a winding thereon, whereby at such points the primary coil and core together with the secondary coil and core and suitable secondary circuit controlling devices coöperate to cause an increase of current in the primary circuit which is utilized to cause actuation of a controlling device, such for example, as a valve.

The primary circuit is preferably connected to one coil of a differentially wound magnet, whose other coil is wound in the opposite direction and connected in shunt to the primary coil. The resultant magnetization of the differential magnet is sufficient to prevent the operation of a biased retarding device such as a weighted valve, but when the current through the primary circuit is increased to such an extent as to neutralize the magnetization of the differential magnet due to the shunt circuit, the biased control device will operate to retard or stop the train or vehicle. The secondary circuit and its core will be mounted opposite the magnetically discontinuous sections of the magnetic circuit such as the ordinary track

rail, which sections may be of manganese steel. The secondary coil and core will be laid close to the non-magnetic sections, and the secondary circuit may be controlled by an ordinary track relay, so that when the block ahead is clear the secondary circuit will be open, but when a train is in the block ahead, the secondary circuit will be automatically closed, at which time the current in the primary coil would be very largely increased by reason of the reduced impedance of the transformer. In case the block ahead is clear, the secondary circuit will remain open and the impedance of the transformer will not be substantially reduced, so that the current flowing in the primary will not be sufficiently increased to neutralize the holding power of the shunt coil of the differential controlling magnet. It will be seen that an increase of the impedance of the primary circuit will not cause the train controlling device to operate.

In the accompanying drawings 1 represents a source of alternating current carried on the vehicle, one side of which is connected by wire 2, safety magnet 3 to terminal 4 of differential controlling magnet 5. The terminal 4 is connected to coil 6 of differential magnet 5 which is connected by wire 7 to the primary coil 8 carried on core 9, the other terminal of primary coil 8 being connected by wire 10 back to the generator or source of supply.

The shunt circuit comprises wire 11 connected to wire 2, thence through bridge 12 carried by the core of magnet 3, thence by wire 13 to coil 14 of differential magnet 5, which coil is wound oppositely to coil 6 and has a larger number of ampere turns. The other end of coil 14 is connected by wire 15 to the return wire 10.

The magnet 5 has a movable core 16, provided with a weight 17 which is held up by the resultant magnetism of the differential coils 6, 14, but when the pull exerted by the magnet 5 drops sufficiently the weight 17 causes the valve stem 16 to drop, and thereby operate the valves in a valve casing 18 to effect stoppage of the train. The specific details of this valve mechanism are not a part of this invention and do not require further description herein.

The core 9 upon leg 19 of which the coil 8 is wound comprises in addition two legs

20, 21 at right angles to each other. The legs 19 and 20 are disposed so as to be in inductive relation to the ordinary steel track rail 22, which is of course magnetic and 5 forms a path in coöperation with the poles 19 and 20 for the normal magnetic flux produced by the current through the coil 8. At control points, such as blocks, there will be a non-magnetic section of track rail 10 24, such as manganese steel and just at one side of the track opposite the non-magnetic sections 24 will be placed a magnetic bridge or auxiliary core 25, herein shown as a U-shaped cross section having its ends ar- 15 ranged in the path of the magnetic flux between poles 21 and 19 of the core 9. 26 is a secondary winding on core 25, having its terminals at mercury cups 27, 28. 29 is a bridging piece adapted to dip into the mer- 20 cury cups and close the secondary circuit, and when lifted up by the magnet 30 opens the secondary circuit. The magnet 30 is contained in a relay circuit 31 which includes the armature 32 of a track coil 33. Track 25 coil 33 is operated in the well known manner being short-circuited when a train is in the block thereby allowing the armature 38 to open the circuit of magnet 30 at contact 34, but when energized closes the cir- 30 35 circuit of magnet 30 at contact 34. When magnet 30 is energized, that is, when the block is clear, the secondary 26 will be open at mercury cups 27, 28, but when magnet 30 is deenergized, as when a train is in the block the bridge 29 will fall by its own weight into the mercury cups and complete the secondary circuit.

When the train is running on the rails 22, it will be seen that the impedance of 40 coil 8 will remain substantially constant by reason of the magnetic flux passing through the rail between poles 19 and 20. When the non-magnetic section 24 is reached, the magnetic circuit will then be between pole 45 19 and core 25 to pole 21, which will not change the impedance of the primary circuit if the secondary 26 is open. This will be the case when the block ahead is clear, and consequently the current flowing in the primary circuit will not vary because the impedance of the whole transformer will not be varied simply by changing the magnetic flux from between poles 19 and 20 to between poles 19 and 21. If, however, the 50 secondary circuit be closed, as when there is a train in the next block, the impedance of the coil 8 will be very greatly decreased, by reason of the closed secondary, thereby permitting an increased current to flow through 55 the primary coil 8. The normal reduced current flowing through primary 8 and differential windings 6 and 14 produces a resultant magnetism sufficient to oppose the pull of weight 17 and thereby prevent op- 60 eration of the retarding device 18, but when

the current through primary 8 is increased the holding power of magnet 5 due to shunt coil 14 is reduced, thereby permitting weight 17 to operate the controlling device. If the circuit of magnet 3 is interrupted, it will 70 be seen that the bridging piece 12 will drop thereby opening both circuits of the differential magnet 5 and allowing the weight to act to stop the train. If the circuit of primary coil 8 be opened the same result will 75 occur, inasmuch as primary coil 8 and magnet 3 are in series. If the circuit of coil 14 is opened the same result will occur inasmuch as the ampere turns of winding 6 will be insufficient to oppose the weight 17. It 80 will be observed that the coil 14 has sufficient ampere turns to support the weight 17, notwithstanding the opposition due to relatively few ampere turns of coil 6, but that the coil 6 will overcome the neutralizing coil 14 sufficiently to permit the weight 17 to operate, when the current is increased in the primary circuit including coil 8, upon passage of the train over core 25 when its secondary is closed. 90

It will be seen that the magnetic circuit of the transformer is practically complete at all times, and means are provided whereby the secondary of the transformer is brought into and out of proper inductive 95 relation to the primary without disturbing the magnetic circuit. The present system is advantageous in that complicated and expensive road mechanism is eliminated together with moving parts, absolute reliability is secured by reason of the differentially wound magnet which upon interruption of any circuit detects its own failures by stopping the train and operating at certain points to effect stoppage of the train by increase of current in the primary circuit. It will also be understood that the locomotive devices can be suitably disposed on one or both sides of the locomotive as may be desired. If disposed on both sides, the connections of coil 8 would be in multiple to the differential magnet 5. While the system has been described herein with reference to the utilization of one or both of the track rails provided with non-magnetic sections, it will 105 be understood that the invention is not necessarily embodied in such arrangement, though this is preferable, because of the reduced cost of installation. 110

Having thus described my invention, what 120 I claim as new and desire to secure by Letters Patent of the United States is:—

1. The combination with a vehicle, of a circuit thereon, a device responsive to increase of current in said circuit, a core having a winding connected in said circuit, means external to the train for normally completing a magnetic circuit including said core, and means external to the train at predetermined points for establishing an alter- 125 130

- native magnetic circuit including said core and reducing the impedance of said vehicle circuit to cause operation of said device.
- 5 2. The combination with a vehicle, of a circuit thereon, a device responsive to increase of current in said circuit, a core having a winding connected in said circuit, means external to the train for normally 10 completing a magnetic circuit including said core, means external to the train at certain points for completing an alternative magnetic circuit for said core, and means associated with said latter means effective to increase the current in said vehicle circuit by reducing the impedance of said winding.
3. The combination with a vehicle, of a circuit thereon, a device responsive to increase of current in said circuit, a core having a winding connected in said circuit, means external to the train for normally completing a magnetic circuit including said core, means external to the train at certain points for completing an alternative magnetic circuit for said core, a winding on said means, and means for short circuiting said winding to effect operation of said device by increase of current through said first winding.
- 30 4. The combination with a vehicle, of a circuit thereon, a coil in said circuit, a track rail, a core carrying said coil and disposed adjacent the track rail so as to have its magnetic circuit completed thereby, a non-magnetic section of track rail, a core adjacent said non-magnetic section for maintaining the magnetic circuit, a winding on said core, means for controlling the circuit of said winding, and a device on said vehicle responsive to variation of current in the vehicle circuit and coil.
5. The combination with a rail having a non-magnetic portion, of a stationary magnetic core adjacent said portion, a magnetic core carried on the vehicle and disposed to have its magnetic flux pass through the rail or through the stationary core without substantial variation, a circuit on the vehicle having a winding on the core carried by the vehicle, a device on the vehicle responsive to increase of current in said winding, a winding on said stationary core, and means for opening and closing the circuit of said winding.
- 55 6. The combination with a vehicle, of a circuit thereon, a coil in said circuit, a track rail, a core carrying said coil and disposed adjacent the track rail so as to have its magnetic circuit completed thereby, a non-magnetic section of track rail, a fixed magnetic core parallel to and adjacent said section of rail, a winding on said core, means effective to control the current in said winding, and a device responsive to variation of current in 60 said vehicle circuit.
7. The combination with a vehicle, of a circuit thereon, a coil in said circuit, a track rail, a core carrying said coil and disposed adjacent the track rail so as to have its magnetic circuit completed thereby, a non-magnetic section of track rail, a fixed magnetic core parallel to and adjacent said section of rail, a winding on said core, means effective to control the current in said winding, and a device including a differential coil in said vehicle circuit.
8. The combination with a vehicle, of a circuit thereon, a coil in said circuit, a core carrying said coil, said core traveling adjacent a relatively stationary magnetic track rail so as to have its magnetic circuit normally completed thereby, a non magnetic rail section, a magnetic core adjacent said non magnetic rail section for completing an alternative magnetic circuit, a differential magnet in circuit with said traveling coil, a controlling device controlled by said magnet, and means including a winding on said stationary magnetic core and a switch for effecting operation of said device when said switch is in a predetermined position.
9. The combination with a vehicle, of a circuit thereon, a coil in said circuit, a core carrying said coil, said core traveling adjacent a relatively stationary magnetic track rail so as to have its magnetic circuit normally completed thereby, a non magnetic rail section, a magnetic core adjacent said non magnetic rail section for completing an alternative magnetic circuit, a differential magnet in circuit with said traveling coil, a controlling device controlled by said magnet, and means for weakening said differential magnet to operate said device at predetermined times, said means including a winding on said stationary magnetic core and a switch controlling said winding.
10. The combination with a vehicle, of a circuit thereon, a coil in said circuit, a core carrying said coil, said core being disposed adjacent a relatively stationary magnetic track rail so as to have its magnetic circuit completed thereby, a non-magnetic rail section, a magnetic core adjacent said non-magnetic section for completing an alternative magnetic circuit, a secondary coil on said magnetic section, means for controlling the circuit of said coil, a differential magnet in circuit with said first coil, a controlling means, and means whereby said differential magnet operates said controlling means when said secondary circuit is closed and the core carried by the vehicle is in position to complete said alternative magnetic circuit.
11. The combination with a vehicle having a circuit, of a core carried by the vehicle having two poles adapted to coöperate with the rail to constitute a magnetic circuit, a stationary core, and a laterally dis-

- posed pole adapted to coöperate with said stationary core to constitute an alternative magnetic circuit, a winding in said vehicle circuit carried by said movable core, and a device responsive to variation of impedance of said winding.
12. The combination with a vehicle having a circuit, of a core carried by the vehicle having two poles adapted to coöperate with the rail to constitute a magnetic circuit, a stationary core, and a laterally disposed pole adapted to coöperate with said stationary core to constitute an alternative magnetic circuit, windings on said stationary and movable cores respectively, means for opening and closing the circuit of the winding on said stationary core, and a device responsive to variation of impedance of the winding on said movable core.
13. The combination with a rail having a non-magnetic portion, a magnetic bridge adjacent said portion, a magnetic core carried on the vehicle having separate poles respectively adjacent said rail and said bridge, a coil on said core, a source of alternating current, means on said vehicle responsive to increase of current through said coil, and external means including a winding on said magnetic bridge for increasing the current.
14. The combination with a vehicle, of a circuit thereon, a coil in said circuit, a core carrying said coil, said core being disposed adjacent a magnetic track rail so as to have its magnetic circuit normally completed thereby, a non-magnetic rail section, a magnetic core adjacent said non-magnetic rail section for completing an alternative magnetic circuit, means for varying the inductive conditions of said traveling core and said stationary magnetic core to vary the current in said coil, and a device carried by the vehicle responsive to such current variation, and also responsive to opening of the circuit of said coil.
- In testimony whereof I affix my signature in presence of two witnesses.
